UNITED STATES PATENT OFFICE.

GEORGE A. JAMES, OF SAN FRANCISCO, CALIFORNIA.

THERMOSTATIC CONTROLLER.

1,201,469.

Specification of Letters Patent. Patented Oct. 17, 1916.

Application filed September 27, 1915. Serial No. 52,846.

To all whom it may concern:

Be it known that I, GEORGE A. JAMES, a citizen of the United States, residing at San Francisco, in the county of San Francisco and State of California, have invented new and useful Improvements in Thermostatic Controllers, of which the following is a specification.

The present invention relates to thermostatic controllers for gaseous fuel.

One object of the invention is to provide such a controller by which some gas, even if a small amount, will always be admitted to the burner; in which the pressure of the gas will be balanced about the valve-actuating mechanism; in which the amount of heat which is transmitted to the controller from the object heated can be varied to vary the sensitiveness of the control; in which the operation of the valve will not be interfered with by the formation of liquid deposits from the gaseous fuel; to provide in such a controller means for accurately adjusting the expansion member; and one in which the pressure of the gaseous fuel itself will be used to lift the valve from off its seat.

A further object of the invention is to provide such a controller in which the temperature at which the controlling mechanism operates will be varied according to whether the fuel is or is not being used to heat a cooking vessel, as to boil water.

In the accompanying drawing, Figure 1 is a vertical sectional view of my improved thermostatic controller applied to a radiator; Fig. 2 is an end elevation of Fig. 1; Fig. 3 is a side view, partly in section, of the controller applied to a gas cooking stove; Fig. 4 is a similar view of the same as applied to an oven.

Referring to the drawing, 1 indicates a steam radiator into which extends a cylindrical plunger 2 leading through a stuffing box 3 having a suitable bearing 4 in which it can slide and connected at its outer end with the casing 6 of a controller 7. To the outer edge of said casing is secured a cover plate 8 having formed therein conduits 9, 10, 50 which are connected to gas pipes 11, 12 leading to and from the controller respectively. The conduit 9 communicates with the interior of the controller by a circular series of small holes 13 the passage of the fuel 55 through which can be controlled by a valve 14 having a stem 16 slidable in a hole situ-

ated centrally with respect to the series of passages. The conduit 10 communicates with the interior of the casing by a hole 17. When the valve is opened, gas can flow 60 through the passages into the controller and out therefrom by the hole 17 into the conduit 10. The valve is made with a mica plate 18 which comes in contact with said seat. It is found that, owing to the low 65 heat conductivity of mica, practically no condensation of the gas takes place on its surface, and owing to the smoothness of said surface no condensed liquid will remain thereon. Consequently the fit of the valve 70 to its seat never becomes impaired by the deposition of condensed gas upon the surface of the valve. Said valve is attached to the free end of an expansion member 19, the other end of which is rigidly secured 75 by rivets 21 and a block 22 to the cover plate. The expansion member is additionally, but adjustably, secured to the cover plate near the block 22 by means of a micrometer screw 23 having two threaded portions 24 and 26 of different pitches screwed 80 respectively through the cover plate and the expansion member. The screw 23 is surrounded by a rubber washer 25 which acts as packing to prevent the escape of gas from 85 the interior of the casing.

Owing to the balanced gas pressure around the valve the valve is never held tightly to its seat, and a small amount of gas always escapes past said valve. It is desired that such should be the case, and if necessary to produce this result, the mica face, or the seat, of the valve is scratched in order to let the gas escape between the valve and its seat.

The temperature at which the controller operates can be varied by moving the plunger rod in or out in its bearing. If it is moved inwardly the amount of heat transmitted to the controller is increased, and therefore the gas is shut off or materially reduced at a lower temperature. If moved outwardly, the contrary is the case.

In the form of the invention shown in Fig. 3 the controller is fixedly supported below a ring gas burner 31 supplied with gas controlled by the controller, and the plunger rod 32 enters a movable cylinder 33, which is extended upwardly to form a stem 34 extended horizontally at the top to form 10 a disk 35, which can support a kettle or the like, a coiled spring 36 being interposed

between the upper end of the cylinder and the plunger rod. If a kettle be deposited upon the disk, the disk is immediately lowered by the weight of the kettle acting 5 against the pressure of the spring 36, and since, in that position, a greater extent of surface of the cylinder is in contact with the plunger rod, a greater proportion of heat is transmitted to the plunger rod and 10 controller. The controller can be so arranged that, when the water in the kettle is at boiling temperature, the gas fuel is automatically shut off or reduced to a minimum.

Fig. 4 shows a modification of the invention as applied to an oven. In this form of 15 the invention the plunger rod carries a pointer 37, which moves over an indicating scale 38, which indicates the temperature at which the interior of the oven should be 20 maintained. By moving the plunger rod in or out, any desired temperature of the oven can be maintained by controlling the supply of gas so as to produce said temperature in the oven.

25 I claim:—

1. A thermostatic controller for fuel gas comprising a casing connected by heat conducting material with an object heated by the combustion of said gas, a thermostatic 30 member in said casing, and a valve controlling the passage of said gas to the object to be heated, and adapted to be raised from its seat by the pressure of the gas, and to be seated by the expansion of said thermostatic 35 member.

2. A thermostatic controller for fuel gas comprising a casing connected by heat con-

ducting material with an object heated by the combustion of said gas, a thermostatic member in said casing, and a valve controlling the passage of said gas to the object to be heated having a mica face to contact with its seat, and adapted to be raised from its seat by the pressure of the gas, and to be seated by the expansion of said thermostatic member.

3. A thermostatic controller for fuel gas comprising a casing connected by heat conducting material with an object heated by the combustion of said gas, a thermostatic 50 member in said casing, and a valve in said casing controlling the entrance of gas into the casing and the passage of said gas to the object to be heated, and adapted to be raised from its seat by the pressure of the gas, and to be seated by the expansion of said thermostatic member.

4. In combination, a ring gas burner, a metallic part extending upwardly therethrough and adapted to contact with a vessel placed upon said burner to be heated thereby, a thermostatic controller fixedly secured relatively to the burner, a second metallic part supported thereby and engaging said first-named part, and a spring between the two parts, supporting the first-named part.

In testimony whereof I have hereunto set my hand in the presence of two subscribing witnesses.

GEORGE A. JAMES.
